[57] CLAIM

The ornamental design for a chair, as shown and described.

DESCRIPTION

FIG. 1 is a front perspective view of a chair showing my design;

FIG. 2 is a side perspective view shown on a reduced scale;

FIG. 3 is a front perspective view shown on a reduced scale;

FIG. 4 is a rear perspective view shown on a reduced scale; and

FIG. 5 is a side perspective view shown on a reduced scale with the backrest rearwardly angled to an alternate position.

FIG. 6 is a front perspective view of a chair showing a second embodiment of my design;

FIG. 7 is a side perspective view;

FIG. 8 is a front perspective view; and

FIG. 9 is a rear perspective view thereof.

The fabric pattern schematically depicted on the seat, back, and armrest portions is continuous throughout.
